SAFETY-LOCK.

1,277,241.

Specification of Letters Patent. Patented Aug. 27, 1918.

Application filed October 11, 1917. Serial No. 196,032.

To all whom it may concern:

Be it known that I, FRANTZ MORTENSEN, a subject of the King of Denmark, residing at Amagerbrogade 257, Copenhagen, Denmark, have invented certain new and useful Improvements in or Relating to Safety-Locks, of which the following is a specification.

This invention relates to locks of the type 10 in which it has been proposed to use a number of tumbler plates which may be moved by means of a key which is irregularly formed at the end.

The object of the invention is to provide 15 a safety lock which will overcome several disadvantages generally present in such locks.

According to this invention the improved safety lock has briefly the following advantages:—

The lock may be operated conveniently and securely from both sides of the door; it is practically speaking impossible to open the lock by means of a false key. One single 25 spiral spring acts as returning means in both the directions in which the locking bolt is moved. The tumbler plates move quite independent of each other. One single spring or a spring on each side of the tumbler plates will automatically effect locking 30 when the ball is pushed out. When locked, the bolt cannot be pushed back. The fixing of the lock is convenient, practical and secure.

35 Referring now to the accompanying drawings which show by way of example one form in which the invention may be carried into effect:—

Figure 1 shows the lock in vertical section and in closed position, fixed to the door.

Fig. 2 is the same as Fig. 1 excepting that the locking bolt is shown in opening position.

Fig. 3 is the same as Fig. 1 excepting that 45 the locking bolt is pushed entirely back, which is the case every time the door is opened and closed.

Fig. 4 is a vertical cross-section of the lock on line 4—4 of Fig. 5 showing the key 50 acting on the tumbler plates.

Fig. 5 is a horizontal section of the lock on line 5—5 of Fig. 4 showing one of the buttons pushing out the lock bolt in order to bring the tumbler plates in locking or 55 dogging position.

Fig. 6 is a horizontal section along line

6—6 of Fig. 4 with the tumbler plates moved in. This view also shows the spring which moves the tumbler plates when the locking bolt is pushed out thus bringing the parts 60 into locking position.

Fig. 7 shows one of the tumbler plates.

Fig. 8 shows the key.

In the form shown in the accompanying drawings, the lock consists of a casing 1 65 having an opening 2 for the lock bolt 3. This bolt has an opening 4 at the rear in which the tumbler plates 5, having either one or two slots 7 at their end, are placed between disks 6. The slots 7 are so arranged 70 that when the key is pushed in, one set of the slots will form a straight line so as to accommodate a stationary fence 8.

The tumbler plates 5 turn on the pivot pin 9 in contact with the disks 6 which are 75 prevented from moving with the plates on the pin. The spiral spring 10 may be used for creating friction between the tumbler plates 5 and the disks 6.

The spring 11 performs a double function. 80 In the first place it will react upon the locking bolt 3 to press the tumbler plates 5 against the fence 8 as shown in Fig. 1, when the parts are in the locking position, so that as soon as the slots 7 at the end of the tumbler plates are brought into opening position by means of the key, the tumbler plates will be moved over the fence, as shown in Fig. 2, through the pressure of the spring 11. In the second place when the door is opened 85 or closed and the locking bolt thereby pushed farther back, the spring will act in the opposite direction and tend to push the locking bolt outward as shown in Fig. 3.

On each side of the casing a key-way 12 90 is arranged for the key 13. The end of the key has an irregular shape, for instance, as shown in Fig. 8. When the key is pushed against the tumbler plates the irregularly shaped end will move each individual tumbler plate into its proper opening position so that one row of the slots 7 comes in line opposite the fence 8. The spring 11 will then move the locking bolt and tumblers and cause the latter slightly to engage with the 95 bridge 8.

In the drawings, the lock is shown as a so-called "ball lock", i. e., when the locking bolt is in the position as shown in Fig. 2 the door may be opened either by pushing or pulling, 100 110 the locking bolt in either case being pressed farther back (see Fig. 3) due to its engage-

ment with the keeper of the door frame. The spring 11 will however again bring the bolt when released into "neutral" position as shown in Fig. 2. Other ways of working the bolt may, however, be used without departing from the spirit of this invention.

The buttons 14 supported upon the springs 15 serve in conjunction with the plunger pins 16 to press out the locking bolt 3 and 10 free the tumblers from engagement with the fence 8, when fastening the lock. By pressing a button a conical part 17 will act on the end of the locking bolt and push it outward, thus disengaging the tumbler plates 15 from the fence. As soon as the tumbler plates are disengaged the spring 18 will immediately bring them into locking position. The action of disengaging the tumbler plates may also be arranged in various 20 ways and the spring 18 may be divided into two springs acting one on each side of the tumbler plates if desired.

The lock is fixed to the door in the manner shown in Figs. 1 and 5. The sides 19 of 25 the casing 1 protrude and overlap the opening in the door in which the lock is fixed. By fixing the lock in this way the door need not be unnecessarily cut and the lock, which is fixed to the door only by means of the 30 screws 20, will fit to practically any door without altering the lock or the key.

In the drawings, the tumbler plates 5 are shown in connection with the movable locking bolt and the fence 8 is stationary, but 35 this arrangement of the tumbler plates and the bridge may be reversed without any inconvenience to the function of the lock.

Having now described my invention, what I claim as new and desire to secure by Letters Patent is:—

1. In combination in a lock, a slidable bolt, a fence-like abutment member, a series of tumbler plates slotted to accommodate said fence, mounted on a pivot pin with intervening spacing disks axially pressable against said tumblers but restrained from angular movement therewith thus providing for independent movement of any tumbler against frictional resistance sufficient 50 to prevent undesired movement, and a push key adapted to operate said tumblers and effect alinement of the slots therein to receive said fence and permit backward movement of said bolt.

55 2. In combination in a lock, a slidable bolt, a fence-like abutment member, a series of tumbler plates slotted to accommodate said fence, mounted on a pivot pin with intervening spacing disks axially pressable 60 against said tumblers but restrained from angular movement therewith thus providing for independent movement of any tumbler against frictional resistance sufficient to prevent undesired movement, a resilient ele- 65 ment for pressing said disks against said

tumblers to automatically compensate for wear, and a push key adapted to operate said tumblers and effect alinement of the slots therein to receive said fence and permit backward movement of said bolt.

3. In combination in a lock, a slidable bolt, a fence-like abutment member, a series of tumbler plates slotted to accommodate said fence, mounted and angularly movable upon a pivot pin, in company with intervening non-rotatable and axially adjustable spacing disks, a push key adapted to operate said tumblers and effect alinement of the slots therein to receive said fence and permit backward movement of said bolt, and a single spring normally retaining said bolt in an intermediate latch position wherein said fence just enters said slots, and permitting, while resiliently opposing, inward or outward movement of said bolt.

4. In combination in a lock, a slidable bolt, a fence-like abutment member, a series of tumbler plates slotted to accommodate said fence, mounted and angularly movable upon a pivot pin, in company with intervening non-rotatable and axially adjustable spacing disks, a push key adapted to operate said tumblers and effect alinement of the slots therein to receive said fence and permit backward movement of said bolt, a single spring normally retaining said bolt in an intermediate latch position wherein said fence just enters said slots, and permitting, while resiliently opposing, inward or outward movement thereof, a resilient push button movable normally of the bolt's movement to push it outward and disengage said fence from said slots, and spring means to rock said tumblers about their axes and lock the bolt in the outward position.

5. In combination in a lock, a slidable bolt, a fence-like abutment member, a series of tumbler plates slotted to accommodate said fence, and of which at least one has two slots so placed that one will be moved into line with said fence when said plate is operated, and a push key insertible from either side of the lock to operate said tumbler plates and effect alinement of a row of slots to receive said fence and permit backward movement of said bolt.

6. In combination in a lock, a slidable bolt, a fence-like abutment member, a series of tumbler plates slotted to accommodate said fence and of which any number are provided with two slots so placed that one slot will be moved into line with said fence when said plates are operated, and a push key insertible from either side of the lock to operate said tumbler plates to effect alinement of a row of slots to receive said fence and permit backward movement of said bolt.

7. In combination in a lock, a bolt slid- 130 able in a casing, a fence-like abutment in

- 5 said casing behind said bolt, a series of tumbler plates slotted to accommodate said fence, mounted in said bolt on a pivot pin with intervening spacing disks axially 55
 5 pressable against said tumblers but restrained from angular movement therewith thus providing for independent movement of any tumbler against frictional resistance sufficient to prevent undesired movement, 60
 10 and a push key adapted to operate said tumblers and effect alinement of the slots therein to receive said fence and permit backward movement of said bolt.
8. In combination in a lock, a bolt slide- 15
 15 able in a casing, a fence-like abutment in said casing behind said bolt, a series of tumbler plates slotted to accommodate said fence mounted in said bolt on a pivot pin with intervening spacing disks axially press- 65
 20 able against said tumblers but restrained from angular movement therewith thus providing for independent movement of any tumbler against frictional resistance sufficient to prevent undesired movement, a 70
 25 resilient element for pressing said disks against said tumblers to automatically compensate for wear, and a push key adapted to operate said tumblers and effect alinement of the slots therein to receive said fence and permit backward movement of 75
 30 said bolt.
9. In combination in a lock, a bolt slide- 35
 35 able in a casing, a fence-like abutment in said casing behind said bolt, a series of tumbler plates slotted to accommodate said fence mounted in said bolt and angularly movable upon a pivot pin, in company with intervening non-rotatable and axially adjustable spacing disks, a push key adapted 80
 40 to operate said tumblers and effect alinement of the slots therein to receive said fence and permit backward movement of said bolt, and a single spring normally retaining said bolt in an intermediate latch 85
 45 position wherein said fence just enters said slots, and permitting, while resiliently opposing, inward or outward movement of said bolt.
10. In combination in a lock, a bolt slide- 50
 50 able in a casing, a fence-like abutment in said casing behind said bolt, a series of tumbler plates slotted to accommodate said fence mounted in said bolt on a pivot pin with intervening spacing disks axially pressable against said tumblers but restrained from angular movement therewith thus providing for independent movement of any tumbler against frictional resistance sufficient to prevent undesired movement, a resilient element for pressing said disks against said tumblers to automatically compensate for wear, and a push key adapted to operate said tumblers and effect alinement of the slots therein to receive said fence and permit backward movement of said bolt.
11. In combination in a lock, a bolt slide- 55
 55 able in a casing, a fence-like abutment in said casing behind said bolt, a series of tumbler plates slotted to accommodate said fence and of which at least one has two slots so placed that one will be moved into line with said fence when said plate is operated, and a push key insertible from either side of the lock to operate said tumbler plates and effect alinement of a row of slots to receive said fence and permit backward movement of said bolt.
12. In combination in a lock, a bolt slide- 60
 60 able in a casing, a fence-like abutment in said casing behind said bolt, a series of tumbler plates slotted to accommodate said fence mounted in said bolt and of which any number are provided with two slots so placed that one will be moved into line with said fence when said plates are operated, and a push key insertible from either side of the lock to operate said tumbler plates and effect alinement of a row of slots to receive said fence and permit backward movement of said bolt.

In testimony whereof I have signed my name to this specification.
